Thos. A. Hill, Inventor

1,025,186. CULVERT. THOMAS A. HILL,
Brooklyn, N. Y., assignor to The Burch
Plow Works Co., Crestline, Ohio, a Cor-
poration. Filed Dec. 28, 1911. Serial No.
668,258.

To all whom it may concern:

Be it known that I, THOMAS A. HILL, a citizen of the United States, residing at the borough of Brooklyn, in the county of Kings and State of New York, have invented certain new and useful Improvements in Culverts, of which the following is a specification, reference being had therein to the accompanying drawing.

My invention relates to improvements in culvert, conduit pipe and ducts of similar character and has particular reference to means for reinforcing and strengthening the same.

Referring to the accompanying drawings, Figure 1 is a perspective view of a length of culvert formed of two interlocking sections. Fig. 2 is a broken section in plan on an enlarged scale showing the arrangement of the reinforcing or strengthening ridges or ribs, and Fig. 3 is an end view of one of the sections.

The culvert illustrated in the accompanying drawings is preferably made in two longitudinal sections 12—13 interlocked in position by the lugs 14—15 in the usual manner. Each section is provided with longitudinal ridges preferably five in number of graduated cross sectional areas, the heaviest ridge extending longitudinally along the crown indicated by the reference character 6, the next longitudinal ridges 5—7 being somewhat smaller and the other two longitudinal ridges 4—8 being of still smaller cross section. Transversely of these ridges are formed ridges such as 9, 10 and 11, and these ridges are preferably heavier at the crown than at their extremities both as to depth and width. They are also preferably alternated short and long as shown to advantage

in Figs. 1 and 2. The greatest strain being along the longitudinal center of each section, the same is taken care of by the increased material of the intersecting ridges in that portion. It will also be observed that the longitudinal ridges are preferably arranged closer together at the longitudinal center of each section than at the sides. By this arrangement the greatest possible strength is secured with the least expenditure of material and weight.

Of course it will be understood that various modifications may be made without departing from the spirit of the invention as set forth in the claims.

I claim:

1. In a tubular conveyer of two longitudinal sections, transverse and longitudinal

ridges upon the outer surface of each section, said transverse longitudinal ridges deeper and wider at the center than at the sides of each section, and said transverse ridges alternating short and long throughout the length of each section.

2. In a tubular conveyer of two longitudinal sections, transverse and longitudinal ridges upon the outer surface of each section, said transverse longitudinal ridges deeper and wider at the center than at the sides of each section, said transverse ridges alternating short and long throughout the length of each section, and said longitudinal ridges closer together at the center than at the sides of each section.

3. In a tubular conveyer of two longitudinal sections, transverse and longitudinal ridges upon the outer surface of each section, said transverse and longitudinal ridges deeper and wider at the center than at the sides of each section, and said transverse ridges alternating short and long throughout the length of each section, said short transverse ridges of smaller cross section than said long transverse ridges.

In testimony whereof I affix my signature in presence of two witnesses,

THOMAS A. HILL.
